SAFETY WINDOW CONSTRUCTION

James Breeze, Stewart Manor, N. Y.

Application May 29, 1951, Serial No. 228,862

1 Claim. (Cl. 20—52.2)

This invention relates to window and sash construction, 15 and particularly to a window wherein the sashes are demountable in a convenient manner, and always safe in operation.

The main object of my invention is to provide a window construction of novel type which allows the sashes to be 20 readily removed for cleaning, painting or other purposes, and as easily replaced when such purpose has been served.

Another object is to provide a window with sashes that are equipped to be automatically retained in any position within the window frame without the use of sash 25 cords, chains or sash weights.

A further object is to have a window frame provided with removable sash guide members which facilitate removal of the sashes and also contribute to the retention of the sashes in attained positions along these guide members when the sashes are raised or lowered.

It is also an object of my invention to introduce what may be termed a safety sash construction for windows that are distinctly modern in form and elegant in style.

An ancillary object is to provide a modern type window construction with safety stop sashes that in general simplifies the manufacture of windows and window frames as such without sacrificing any feature normally present in an ordinary window.

It is, withal, an object to have a safety sash construction for windows which makes the sashes easy to handle and place in position and also reasonable in cost.

Other objects and advantages of the invention and accruing from its application in practice will appear in further detail as the specification proceeds.

In order to facilitate ready comprehension of the invention for a proper appreciation of the salient features thereof, it is illustrated on the accompanying drawing forming part hereof, and in which:

Figure 1 is a perspective view of the safety sash window made according to the invention and embodying the same in a practical form, the view showing the window from the inside;

Figure 2 is a transverse section taken on line 2—2 in Figure 1 and showing details of construction;

Figure 3 is a vertical section taken on line 3—3 in the same Figure 1; and

Figure 4 is another vertical section taken on line 4—4 in Figure 1.

Throughout the views, the same reference numerals indicate the same or like parts.

It is well known that in this country, windows usually are so constructed that two sashes are vertically slidable so as to be raised or lowered in order to close or open the window involved. The sashes are counterbalanced by sash weights connected to the sashes by sash cords or chains which frequently break and allow the sashes to drop in a dangerous manner. Even if no serious damage has been caused by such dropping of a sash, it is still a troublesome procedure to open the window frame, remove the sash and replace the broken sash cords or chains. The window frame itself must always be es-

2

pecially constructed to accommodate the sash weights and have pulleys for the cords or chains, and this means extra cost and waste of space and material in a manner that runs counter to modern trends.

Upon considering this problem, it has occurred to me that window sashes should be readily removable as well as perfectly safe in operation so as to be virtually fool proof and always accessible and convenient to manipulate. As a result of such consideration, I have succeeded in 10 originating a safety sash construction for windows which I shall now proceed to describe in the following.

Hence, in the practice of my invention, and referring now again to the drawing, a window frame, generally indicated at 5, primarily consists of the two opposite upright side walls 6, 6, the top 7 and the bottom member or sill 8 secured together to form a box structure for containing the sashes. An outer sill 9 is also provided, together with the outer frame members 10, 10 and upper outer frame member 11 to complete the frame as a whole, other details and parts being passed by for the present purpose.

However, it is to be noted that no provision need be made for sash weights or cords, nor is any pulley present in the frame. Instead, the latter may be provided with 20 a pair of opposite metal sash guides 12, 12 of L-shaped section as best seen in Figure 2. These guides rest against the outer frame members 10, 10 which thus serve as stops for the same to locate them, while a pair of upper and lower screws 13, 14 in the upper and lower ends of the guides serve to hold them in place within side walls 6, 6 of the frame. A sash 15 is slidable between the guides 12, 12, forming the outer sash of the window, and may be moved along the entire length of the slides at will. At the top, an upper transverse channel member 16 overlies the upper portions of the vertical guides 12, 12, and is not screwed or nailed in place, but held in position by the upper portions of a pair of inner guides or channels 17, 17 for an inner sash 18 held against side walls 6, 6 by upper and lower screws 19 and 20. The lower portions of channels 17 rest upon a bottom member 21 seated in sill 8 and provided with an upwardly extending rib 22 fitting into a bottom groove 23 in sash 18 to serve as weather seal.

Thus far, the outline of the invention does not include a means for retaining the sashes in attained positions of elevation, but this purpose is served in a special manner, now to be set forth. In each of the upright guides 12, 12 and channels 17, 17 are provided a series of recesses 24, 25 serving as stops for the sashes. The latter are each provided upon the opposite side edges engaging in the guides and channels, with a spring catch 26 biased outward by a coil spring 27 and tending to seat in any one of a series of recesses or stops 24 or 25, depending upon which guide or channel is engaged. The net result is that sashes when raised to any position along their guides will have their spring catches successively engaged in the recesses as they are moving up or down, and when left in a given position, the catches will engage in the recesses in that position and hold the sash involved stationary. Thus, at every step, the force of gravity will be checked and prevented from drawing the sashes down from any attained position, and obviously, no counterbalancing sash weights will be necessary in such a window.

In other words, the sashes are automatically stopped and held in position at any elevation, and cannot drop and are therefore very safe and convenient to use.

On the other hand, another factor of safety is inherent in the present safety sashes, namely, the fact that a slight noise is produced whenever the safety catches of either sash pass the recesses in the guides prevents burglars from silently opening the window and stealing into the house thus equipped. This is true in addition to the fact that

the construction as a whole is very simple and low in cost. Furthermore, when it is desired to clean or paint the two sashes, they may readily be removed and the cleaning or painting done from the inside. In this connection, it is to be noted that if the upper and lower screws 19 and 20 are removed from guide or channel 17 shown in Figure 1, the channel may be removed as indicated in broken lines in Figure 2, when the sash 18 may thereafter also be moved inwardly at the side where the channel has been taken out. The sash may thus be removed altogether and dealt with as a distinct independent object, and as the vertical guide 12 at the left then is exposed with its sash 15, the latter may similarly be removed inwardly without displacing either of guides 12, 12. The upper transverse channel 16, however will be removed with sash 15, as it is also exposed to view when sash 18 and the one guide channel 17 are first removed. The sashes may, of course be similarly replaced.

From the foregoing, it is evident that the safety sashes made according to my invention render the window easy to handle for all purposes and safe as well, so that it is convenient to clean or paint without danger and as conveniently restored to operation after such cleaning or painting. Naturally, the window to which the invention is applied is not limited to any one size or to any certain proportions of width and length, and may be suitable for small and large dwellings, and the sashes themselves may be made of wood frames with glass lights or metal frames with glass or plastic panes if desired.

Manifestly, variations may be resorted to and modifications introduced, while parts may be omitted or used without others within the scope of the appended claim.

Having now fully described my invention and disclosed the manner in which it is made and used, I claim:

A safety window construction comprising a frame having a sill, in combination with a pair of vertical outer sash guide angles connected to the frame sides by means of

screws and extending from adjacent the sill to adjacent the top of the frame, an upper transverse channel member abutting the upper transverse portion of the said frame and having interlocking means for removably retaining the said transverse channel member by means of the said guide angles, a second pair of inner sash guide channels attached to the said frame by means of screws and parallel to the outer angles and forming therewith outer channels, a pair of sashes, one slideable in the so formed outer channels and one slideable in the inner channels whereby removal of the screws holding one inner sash guide channel permits the removal of both sashes, a lower transverse angle-shaped member, the horizontal leg of the said lower transverse member abutting the sill with the other leg extending normally thereto and upwardly and inwardly of the said sill, and the said lower transverse member having interlocking means for removably retaining the said lower transverse member by means of the said inner guide channels, an intermediate vertical weather strip extending from the horizontal leg of the said lower transverse member to coat with a groove in the said sash bottom, the bottom portion of the said lower transverse member forming an acute angle with the surface of the said sill.
